United States Patent Office.

WILLIAM L. BEARDSLEY, OF BINGHAMTON, NEW YORK.

Letters Patent No. 65,048, dated May 28, 1867.

IMPROVED LATHING APPARATUS.

The Schedule referred to in these Letters Patent and making part of the same.

TO ALL WHOM IT MAY CONCERN:

Be it known that I, WILLIAM L. BEARDSLEY, of Binghamton, in the county of Broome, and State of New York, have invented a new and useful Apparatus for Lathing Rooms; and I do hereby declare that the following is a full, clear, and exact description thereof, reference being had to the annexed drawings, making a part of this specification, in which—

Figure 1 is a perspective view of the apparatus.

Figure 2 represents the front side with the pieces of lath in position.

Similar letters of reference indicate corresponding parts in each figure.

My invention consists in the construction and use of an apparatus for placing and holding several pieces of lath in position at once, until nailed to the studs or joist, thereby facilitating the operation and insuring more regularity in the work.

I will describe its construction and operation.

I construct my lath-holder A of suitable timber, of the proper size and thickness to be easily handled, and capable of holding ten or more pieces of lath, which are held in their position by means of nine or more fingers B B B working in the parallel slots C C, running lengthwise near the edges of the holder. These fingers are placed the width of the strip of lath apart, and attached to and held in their relative position by an elastic braid, D, working in a groove in the side of each of the parallel slots C C. I then make another slot, E, in the end of the holder, into which I place a spiral spring of sufficient strength to contract all the fingers, and hold the pieces of lath in their places. To accomplish this, I attach to the free end of said spring a movable shoulder, F, which is placed on a line with the two end fingers B B, so that when the last piece of lath is placed in its position, it will be necessary to draw back the spring and shoulder to receive it. For the purpose of holding the first piece of lath in its position, I attach two stationary shoulders G G on a line at the upper end of the parallel slots C C. In the centre and on the transverse line of the shoulders I place a key or button, H, operated from the opposite side, for the purpose of holding the apparatus in position while nailing. The holder A is tapered at the end. Near this tapered end I cut through the board a slot, I, for an eccentric lever, J, to work in, held in its position by the pin-blocks L L.

When I use my improvement, I place the strip of lath K between the fingers B B, commencing at the stationary shoulders G G, and continuing until the holder is filled, with the exception of the last piece, the edge of which is placed against the movable shoulder F, and the spring drawn back until the other edge passes over the fingers B B, thereby contracting all the fingers and holding the ten or more pieces of lath to be placed in position for nailing, which is accomplished by placing the lower part of the holder A on the casing or base-board, and the lath against the studs. I then nail the upper piece and turn down the bottom H, which holds the apparatus in its position while nailing the others. I then remove the holder, fill it again, and reverse the operation by turning up the hook or button H and resting the apparatus upon it. The eccentric lever J is then turned down for the purpose of holding it in a perpendicular position, or against the joists. The operation may be facilitated by using two or more holders, one person filling and the other nailing. In this manner two persons will accomplish more than four persons operating in the ordinary manner in the same time.

What I claim, and desire to secure by Letters Patent, is—

The construction and use of the apparatus herein described and set forth.

W. L. BEARDSLEY.
